his ATTORNEY.

UNITED STATES PATENT OFFICE.

ROBERT S. PEELLE, OF HOLLIS, NEW YORK, ASSIGNOR TO THE PEELLE COMPANY, OF NEW YORK, N. Y., A CORPORATION OF NEW YORK.

ELECTRIC INTERLOCK FOR ELEVATOR DOORS.

Application filed April 27, 1928. Serial No. 273,350.

My invention relates to electric interlocks for elevator doors, and more particularly to a construction in which the interlock acts to positively prevent the release of the door lock at all times excepting when an elevator car is at a landing closed by the door in connection with which the interlock is used.

Heretofore it has been a common practice to use electric interlocks for the purpose of preventing the application of power to the motor for actuating the elevator, until all elevator doors in a shaft are closed and mechanically locked. Such interlocks have also been made, having a movable contact carrying member which, when the door is fully closed, will mechanically interlock with a member operative upon the door lock so as to prevent the release of the lock to permit opening of the doors unless such movement of the lock is accompanied by a positive mechanical movement of the movable member of the interlock to interrupt the circuit controlled thereby.

This construction is designed to prevent an elevator operator blocking the interlock in a position where, notwithstanding the actuation of the door lock and the opening of the door, power may still be applied to the elevator motor.

In all electric interlock structures heretofore used, the function of the interlock was solely to control the power to the elevator motor, suitable safeguards in some instances being provided to ensure a proper actuation of the interlock in the performance of this function.

With the above conditions in mind, I have provided an electric interlock mechanism which, in the usual manner, may be actuated by the locking mechanism of the elevator doors to control the application of power to the elevator motor, but which, in addition thereto, is so constructed as to place the lock for the elevator door under the control of an electric interlock and permit the actuation of the door lock to permit the opening of a door, and of the interlock itself, only when an elevator car is at the landing closed by the particular door with which the interlock is associated.

By this construction, I not only add all of the safeguards attendant upon the use of the ordinary interlock and of the special interlock which is mechanically connected with

the door lock when the doors are closed, but provide the additional safeguard of positively preventing the actuation of the lock or of the interlock unless a car is properly positioned with its platform substantially flush with the sill of a door opening. 55 60

By this construction it is possible, when desired, to provide means whereby the door lock may be actuated from either the shaft or the floor side of the doors, thus particularly adapting the invention to use upon doors 65 closing a shaft opening in which the elevator car is operated without an attendant within the car, a type of installation which is coming into more general use at the present time. The actuation of the lock of the 70 door from the floor side, is made possible solely from the fact that the locking mechanism is controlled through the electric interlock mechanism and can be actuated only when the elevator car is so positioned as to 75 operate upon the interlock mechanism in a manner to permit not only its actuation, but that of the elevator door lock as well.

The invention consists primarily in an electric interlock for elevator doors of the 80 type including oppositely and vertically slidable sections and a guide rail therefor, embodying therein a locking mechanism for said door sections, a movable contact actuating member, co-operating interlocking devices carried by said member and said locking mechanism, whereby the setting or the release of said locking mechanism will impart positive movement to said member, means normally preventing movement of 90 said member and said locking mechanism, and means operative upon said last named means and engageable by a member upon an elevator car, whereby said locking mechanism may be actuated to permit the opening of the door and to impart movement to said member only when an elevator car is at the landing closed by said door; and in such other novel features of construction and combination of parts, as are hereinafter 95 set forth and described, and more particularly pointed out in the claims hereto appended.

Referring to the drawings,

Fig. 1 is a condensed view from the shaft 105 side of an elevator door equipped with an electric interlock embodying the invention;

Fig. 2 is a side view thereof;

Fig. 3 is a horizontal section adjacent the side of the door at which the interlock is mounted; and

Fig. 4 is a vertical section at the meeting line of the two door sections showing the construction permitting the release of the locking mechanism and the actuation of the interlock under proper conditions, from the floor side of the door.

10 Like numerals refer to like parts throughout the several views.

In the accompanying drawings the invention is shown in connection with an old and well known type of counterbalanced elevator door which includes oppositely and vertically slidable sections, the upper section being shown at 10 and the lower section at 11. The guide rail structure at one side of the door opening is shown in Figs. 1 15 to 3, this structure consisting of the usual wall angle 12 and guide angle 13.

Each door section is provided with the usual flame angle 14 and usual shoes such as 15 co-operating with the guide structure in 25 the usual manner.

A more detailed description of the door structure proper need not be entered into as such is old and well known in the art to which this invention relates. Suffice it to 30 say that in the doors of the type above referred to, flexible connections extend from adjacent the top of the lower section about suitable sheaves on the guide rail structure to adjacent the bottom of the upper section, 35 such not being shown in the drawings.

The above detail is mentioned in order to make it apparent that a locking mechanism carried by one section operative upon the other section, or carried by either section co-40 operating with the guide rail structure, may be effectively used to prevent the opening of the door except when desired.

My present invention is not limited to any particular construction of locking mechanism so long as this mechanism includes a 45 laterally extending member which, by engagement with a movable contact carrying member of the electric interlock proper, will prevent the actuation of the locking mechanism in either setting or releasing same, unless accompanied by an actuation of the movable contact carrying member of the interlock proper to close the circuit to the elevator actuating motor, or interrupt this circuit.

In the accompanying drawings, I have illustrated the invention in connection with a well known type of center lock which consists of a hooked latch member and its actuating handle 16, carried by the upper door section 10 in engageable relation with the top bar structure of the lower door section 11. This member 16 has connected therewith a laterally extended slide 17.

65 The interlock mechanism proper includes

a pivotal member 18, mounted in a suitable housing 19, said member 18 and the slide 17 of the locking mechanism being provided with co-operating interlocking devices consisting of the hook 21 on the slide 17, and the projecting hooked end 20 upon the member 18, see Fig. 1.

When the locking mechanism is set to hold the doors in the closed position, the devices 20 and 21 are mechanically interlocked so that the locking mechanism cannot be actuated to permit the disengagement of the latch 16 from the door section 11 unless the movement of said latch member is accompanied by a movement of the member 18, 75 which carries the movable contact 22 of the interlock proper. This contact member 22 is a bridge contact co-operating with fixed contacts 23 and 24 of said mechanism, which arrangement is old and well known in the 80 art.

The housing 19 is provided with the usual striker member 25 for ensuring the actuation of the slide 17 and the latch 16 upon the closing movement of the door to ensure 90 the proper engagement of the latch member 16 with the top bar structure of the lower door section 11, and of the hook 21 upon the slide 17 with the hooked end 20 of the member 18.

The means for ensuring a proper positioning of the member 18, following the actuation of the slide 17, are old and well known in this art and need not be described. In fact, all of the mechanisms heretofore described form no part of the present invention, except in combination with other controlling mechanisms which will ensure a new mode of operation thereof as a result of their functioning being determined by the 100 position of the elevator car in relation thereto.

While these mechanisms will prevent the blocking of the member 18 so as to prevent the interruption of the circuit controlled thereby with the release of the locking mechanism, no means are provided by which the actuation of such mechanisms is controlled by the position of the car itself. So long as the operator of a car can reach the locking mechanism, the doors may be opened or closed. With this construction alone, it is impossible to provide means accessible from the floor side of the door whereby the locking mechanism may be released without the 110 possibility of the doors being opened when the elevator car is not at the landing of the opening closed thereby.

By means of the interlock construction of my present invention, while the functioning 125 of the interlock proper and the latch mechanism, so far as an assured simultaneous action thereof is concerned, is the same as heretofore, the timing of such actuation is under the control of the elevator car, it be- 130

ing impossible to actuate the locking mechanism or the interlock proper except when a car is at the landing of the door opening, the doors of which it is desired to open. 5 This condition permits the use of an uncontrolled releasing mechanism for the lock mechanism, operable from the floor side of the doors without any possibility of the doors being opened except when a car is in 10 the proper position in relation to the landing.

In securing the above results, I provide means normally preventing movement of the member 18 and of the latch member 16 consisting of a lateral extension or heel 26 carried by and movable with the member 18, and a pivotal locking member 27 carried by the housing 19 in engaging relation with the extension 26. This member 27 is normally projected by a spring 28 into the path 20 of movement of the projection 26 with the member 18, outwardly of the housing 19, without which movement the latch 16 can not be released.

25 Operative upon the member 27 is a rocking lever 29, pivoted at 30 upon the housing 19, and pivoted to said member 27 at 31.

Carried by the lever 29 is an adjustable arm 32 carrying an impact roller 33, engageable by a cam 34 which is carried by the elevator car. The arm 32 is adjustable in relation to the lever 29 by means of set screws 32^a and 32^b carried by said arm and bearing against shoulders upon the end of 35 the lever 29. The cam 34 may be a fixed cam or a receding cam as desired, both forms of such cams being common in the elevator door art.

It will be noted that the member 27 is a 40 mere restraining member acting to prevent movement of the contact actuating member 18 by being interposed in the path of movement of the projection or heel 26 carried by said member. Consequently, the actuation 45 of the lever 29 by the cam 34, in the event that a fixed cam is used, has no operative effect excepting to momentarily create a condition where the locking mechanism may be actuated to permit movement of the door sections. If the locking mechanism is not 50 so actuated, the member 27 is immediately restored to its operative relation to the co-operating means 26 with the passing of the cam 34 out of the operative relation to the impact roller 33. With the stoppage of the car, however, with the cam 34 engaged with 55 said roller, the member 18 is permitted to have movement, and consequently the locking mechanism may be actuated.

60 The above condition permits the utilization of a locking mechanism actuating means accessible from the floor side of the door. This means, in the form of the invention shown, consists merely of a pivoted lever 35, mounted upon a bracket 36 carried by an

astragal 37 of the upper door section, the end 38 of this lever projecting between the two door sections into engaging relation with the latch member 16. The lever 35 has an operating handle 39.

70 It will be noted that when the cam 34 is not operatively engaged with the roller 33, a roller being used merely because of its anti-friction properties, the member 27, acting through the member 18, the interlocking devices 20 and 21, the slide 17 and the latch member 16, will prevent movement of the member 35 sufficient to release the locking mechanism and permit the opening of the door.

80 The operation of the herein described mechanism is substantially as follows:—

In the accompanying drawings, a door is shown in the closed position, the latch member 16 upon the door section 10 engaging 85 the keeper portion upon the lower section 11, so as to prevent the separation of the sections. When the locking mechanism is thus set, the slide 17 is projected laterally to the full extent so as to act upon the pivotal member 18 in a manner to maintain the engagement of the contact 22 with the contacts 23 and 24 to close the circuit controlled thereby.

Hence power can be applied to the elevator cars assuming that all other doors in the shaft are closed with their various parts in the same relation as described.

95 It will be noted that when the parts are in this position, the devices 20 and 21 are 100 mechanically interlocked, and that the spring 28 maintains the member 27 in a position where the lower end thereof is interposed in the path of movement of the extension or heel 26 upon the member 18.

105 With this condition, sufficient movement of the latch member 16 to disengage it from its keeper is prevented as a result of the interlocking relation of the devices 20 and 21, and the restraint placed upon the pivotal 110 movement of the member 18 by the member 27. As a consequence, the locking mechanism cannot be released to permit the opening of the door. In other words, while the locking mechanism is relied upon to control 115 the functioning of the circuit controlling means of the electric interlock, the construction and arrangement of parts of this interlock are such as to normally prevent the release of the locking mechanism except when 120 a car is at the landing closed by the door.

When a car is brought to the floor at which a door is located and comes to the proper position in relation to the door opening, the cam 34, by engagement with the 125 roller 33, will oscillate the lever 29 and therethrough the member 27, moving this member against the tension of the spring 28 to an extent to move the lower end thereof out of the path of movement of the exten- 130

sion or heel 26. When this condition is established, the locking mechanism may be released so as to permit the separation of the doors, the slide 17, however, being so actuated as a result of this releasing action of the locking mechanism as to move from the housing 19, and during this movement to draw the pivotal member 18 outwardly of said housing as a result of the mechanical 10 interlocking relation of the devices 20 and 21, the movement of said member being sufficient to disengage the contact 22 from the contacts 23 and 24. This will interrupt the circuit controlled by these contacts, in which 15 circuit the motor for actuating the elevator is included.

As the doors are opened, the slide 17 will pass out of the range of the opening in the housing 19 through which it passes to engage the member 18, the height of the opening in the housing 19 being such as to prevent the slide 17 re-passing therethrough without a resetting of the locking mechanism.

25 Since power cannot be applied to the car while the contacts 22, 23 and 24 are disengaged, the cam or shoe 34 will remain in its engaging relation with the roller 33 to maintain the parts as above described so long as 30 the door is open. When closing the doors, the end of the slide 17, by engagement with the striker plate 25, will be brought to a position where the latch member 16 is in engaging position with its keeper upon the 35 section 11, and the end of the slide 17 is in register with the opening through the housing 19, at which time the interlocking devices 20 and 21 will be in engaging relation with each other.

40 When these parts are in this position, the slide 17 will be automatically moved into engageable relation with the member 18, and will actuate this member so as to close the contacts 22, 23 and 24. When the contacts 45 are so closed, power may be applied to the car, and following the initial upward or downward movement thereof, the cam or shoe 34 will pass out of its engaging relation with the roller 33 and thus permit the 50 spring 28 to project the lower end of the member 27 into the path of movement of the extension or heel 26 of the member 18, and cause the interlock to place a positive restraint upon the actuation of the locking mechanism so long as the parts remain in 55 this position.

The foregoing description is based upon the assumption that there is an attendant upon the elevator car, but if the elevator 60 installation includes what is known as "hall controls" by which the car may be actuated without the presence of an attendant in the car, it is necessary to actuate the locking mechanism from the floor side of the door. 65 This may be done by means of the lever 35,

the oscillation of which will actuate the latch member 16 in the same manner as though this member were actuated from the shaft side of the door. It will be noted that the same conditions which prevent the 70 actuation of the locking mechanism from the shaft side of the door except when the cam or shoe 34 is in engaging relation with the roller 33, will prevent the actuation of the lever 35 from the floor side of the door so 75 that this lever 35 may be included in the door structure with the full assurance that the door cannot be opened unless a car is at the landing closed thereby.

When the locking mechanism is actuated 80 from the shaft side, the control of this mechanism by the interlock is a mere incidental feature to guard against the tendency of the elevator attendant to release the lock while the car is still in motion and thus 85 prematurely interrupt the circuit to the car motor. The condition as to the locking mechanism actuating means accessible from the floor side of the door is entirely different, since were it not for the control of the 90 locking mechanism by the interlock, the door might be opened at any time and thus introduce hazards not only due to the opening of the door, but to the unwarranted interruption of the power to the elevator car. 95

I believe that the placing of the locking mechanism of the car under the control of an electric interlock mechanism is broadly novel, irrespective of the detailed construction of the lock mechanism. While a center 100 lock mechanism is shown in the accompanying drawings, it is obvious that the invention is not limited to this construction of lock mechanism.

In fact, in the construction shown, the 105 slide 17, by the engagement of its upper face with the top of the opening through the housing 19, itself acts as a sliding lock very similar to one type of old and well known elevator door lock.

It is likewise immaterial whether the locking mechanism be placed upon the upper or the lower section, since in elevator doors of the type in connection with which my invention is used, it is merely necessary to 115 lock one of the door sections, since the weight of these doors is such as to prevent the opening of the door so long as one of the sections is locked. This is due to the fact that the two sections are connected in 120 the manner above described, and the weight of one section is required to counterbalance the weight of the other section.

The use of single panel doors in elevator shafts is so infrequent that the use of the 125 invention in connection with such requires little consideration, but it is obvious that the invention may be readily adapted to a door of this type if desired, without departing from any of its essential characteristics. 130

It is therefore not my intention, to limit the invention to the precise details of construction shown in the drawings, it being apparent that such may be varied without departing from the spirit and scope of the invention.

Having described the invention, what I claim as new and desire to have protected by Letters Patent, is:—

10. 1. An electric interlock for elevator doors of the type including oppositely and vertically slidable sections and a guide rail therefor, embodying therein a locking mechanism for said door sections, a movable contact actuating member, co-operating interlocking devices carried by said member and said locking mechanism, whereby the setting or the release of said locking mechanism will impart positive movement to said member, means normally preventing movement of said member and said locking mechanism, and means operative upon said last named means and engageable by a member upon an elevator car, whereby said locking mechanism may be actuated to permit the opening of the door and to impart movement to said member only when an elevator car is at the landing closed by said door.
20. 2. An electric interlock for elevator doors of the type including oppositely and vertically slidable sections and a guide rail therefor, embodying therein a locking mechanism for said door sections, a movable contact actuating member having an extension or heel thereon, co-operating interlocking devices carried by said member and said locking mechanism, whereby the setting or the release of said locking mechanism will impart positive movement to said member, a locking member co-operating with said extension or heel, whereby movement of said member and said locking mechanism is normally prevented, means operative upon said locking member and engageable by a member upon an elevator car, whereby said locking mechanism may be actuated to permit the opening of the door and to impart movement to said member only when an elevator car is at the landing closed by said door, and locking mechanism actuating means accessible from the floor side of the door.
30. 3. An electric interlock for elevator doors of the type including oppositely and vertically slidable sections and a guide rail therefor, embodying therein a locking mechanism for said door sections, a movable contact actuating member having an extension or heel thereon, co-operating interlocking devices carried by said member and said locking mechanism, whereby the setting or the release of said locking mechanism will impart positive movement to said member, a locking member co-operating with said extension or heel, whereby movement of said member and said locking mechanism is normally prevented, and means operative upon said locking member and engageable by a member upon an elevator car, whereby said locking mechanism may be actuated to permit the opening of the door and to impart movement to said member only when an elevator car is at the landing closed by said door.
40. 4. An electric interlock for elevator doors of the type including oppositely and vertically slidable sections and a guide rail therefor, embodying therein a locking mechanism for said door sections, a movable contact actuating member having an extension or heel thereon, co-operating interlocking devices carried by said member and said locking mechanism, whereby the setting or the release of said locking mechanism will impart positive movement to said member, a pivotal locking member co-operating with said extension or heel, whereby movement of said member and said locking mechanism is normally prevented, and a lever one arm of which is operatively connected with said pivotal locking member, and the other arm of which has an impact member thereon engageable by a member upon an elevator car, whereby said locking mechanism may be actuated to permit the opening of the door to impart movement to said member only when an elevator car is at the landing closed by said door.
50. 5. An electric interlock for elevator doors of the type including oppositely and vertically slidable sections and a guide rail therefor, embodying therein a locking mechanism for said door sections, a movable contact actuating member, co-operating interlocking devices carried by said member and said locking mechanism, whereby the setting or the release of said locking mechanism will impart positive movement to said member, means normally preventing movement of said member and said locking mechanism, means operative upon said last named means and engageable by a member upon an elevator car, whereby said locking mechanism may be actuated to permit the opening of the door and to impart movement to said member only when an elevator car is at the landing closed by said door.
60. 6. An electric interlock for elevator doors of the type including oppositely and vertically slidable sections and a guide rail therefor, embodying therein a locking mechanism for said door sections, a movable contact actuating member having an extension or heel thereon, co-operating interlocking devices carried by said member and said locking mechanism, whereby the setting or the release of said locking mechanism will

impart positive movement to said member, a pivotal locking member co-operating with said extension or heel, whereby movement of said member and said locking mechanism is normally prevented, a lever one arm of which is operatively connected with said pivotal locking member, and the other arm of which has an impact member thereon engageable by a member upon an elevator car, whereby said locking mechanism may be actuated to permit the opening of the door to impart movement to said member only when an elevator car is at the landing closed by said door, and locking mechanism actuating means accessible from the floor side of the door.

7. An electric interlock for elevator doors of the type including oppositely and vertically slidable sections and a guide rail therefor, embodying therein a pivoted latch member upon one of said door sections, a keeper upon the other of said door sections co-operating therewith, a slide having a hook thereon operatively connected with said latch member, a movable contact actuating member having an extension or heel thereon, and having a projecting hooked end co-operating with the hook upon said slide, whereby the setting or the release of said latch member will impart positive movement to said contact actuating member, a pivotal locking member co-operating with said extension or heel, whereby movement of said contact actuating member and said latch member is normally prevented, a lever one arm of which is operatively connected with said pivotal locking member, and the other arm of which has an impact member thereon engageable by a member upon an elevator car, whereby said locking mechanism may be actuated to permit the opening of the door to impart movement to said member only when an elevator car is at the landing closed by said door, and means accessible from the floor side of the door and operative upon said latch member, whereby when an elevator car is at the landing closed by said door said latch mechanism and said slide may be actuated to permit the opening of the door and cause the opening of the circuit controlled by said movable contact actuating member.

40 upon an elevator car, whereby said locking mechanism may be actuated to permit the opening of the door to impart movement to

said member only when an elevator car is at the landing closed by said door.

8. An electric interlock for elevator doors of the type including oppositely and vertically slidable sections and a guide rail therefor, embodying therein a pivoted latch member upon one of said door sections, a keeper upon the other of said door sections co-operating therewith, a slide having a hook thereon operatively connected with said latch member, a movable contact actuating member having an extension or heel thereon, and having a projecting hooked end co-operating with the hook upon said slide, whereby the setting or the release of said latch member will impart positive movement to said contact actuating member, a pivotal locking member co-operating with said extension or heel, whereby movement of said contact actuating member and said latch member is normally prevented, a lever one arm of which is operatively connected with said pivotal locking member, and the other arm of which has an impact member thereon engageable by a member upon an elevator car, whereby said locking mechanism may be actuated to permit the opening of the door to impart movement to said member only when an elevator car is at the landing closed by said door, and means accessible from the floor side of the door and operative upon said latch member, whereby when an elevator car is at the landing closed by said door said latch mechanism and said slide may be actuated to permit the opening of the door and cause the opening of the circuit controlled by said movable contact actuating member.

70 In witness whereof I have hereunto affixed my signature this 25th day of April, 1928.

ROBERT S. PEELLE.
